UNITED STATES PATENT OFFICE

HENRY K. McCONNELL, OF RICHMOND, VIRGINIA, ASSIGNOR TO TOBACCO BY PRODUCTS & CHEMICAL CORPORATION, A CORPORATION OF DELAWARE

RECOVERY OF NICOTINE

No Drawing.

Application filed November 29, 1921. Serial No. 518,593.

This invention relates to improvements in processes for the recovery of nicotine from its compounds and especially from its salts.

While many ways are known for the recovery of nicotine from its salts, all of them so far as I am aware, are in the nature of purely laboratory processes, giving a low return unless carried out with great care and skill.

The object of the present invention is to provide a relatively simple process which can be carried out on a large scale, with certainty of a good output at a cost which will make the process satisfactory for the recovery of nicotine as a commercial matter.

15 The invention will be readily understood from the following detailed description of one specific process which is the best embodiment of the invention now known to me.

The starting material is a suitable compound containing nicotine such as, for example, a salt or salts of nicotine. Generally such a salt as the sulphate, chloride, acetate or nitrate of nicotine, is available. Usually the nicotine sulphate is most readily obtained 25 in large quantities, and I therefore describe the specific process employing nicotine sulphate as the starting material, it being understood, however, that the other salts may be used instead of the sulphate.

30 The nicotine sulphate is usually in the form of an aqueous solution and generally of about 40% strength by weight. If stronger than this, it may well be diluted to bring it to this strength, or if weaker it may be evaporated, for example, in a vacuum pan, to bring it to the said strength.

To ten parts by weight of this solution of 40% strength, I add $2\frac{1}{2}$ parts by weight of freshly hydrated lime in powder form 40 ($\text{Ca}(\text{OH})_2$) and then thoroughly stir or agitate the mixture. This is best done by grinding the mixture, for example, in a ball or pebble mill. By the use of the pebble mill running at a normal speed the mixing can be 45 done in about ten minutes.

Then I add to the mixture a carbonate or hydroxid of an alkali metal. In the commercial practice I have found that a good soda ash is particularly suitable. When using 50 soda ash, I add it in the proportion of 1 to

1 $\frac{1}{2}$ parts by weight to the above mixture and then agitate or stir it well. When the ball or pebble mill is used as above described, the soda ash may be added to the mixture in the mill, after the first grinding, and then a further grinding step carried out for a short time, so as to thoroughly incorporate the soda ash. Usually five minutes will suffice for this. At the end of this mixing the product is usually a semisolid material of such a consistency that it will hold the pebbles in an upright position. Then I add to the material in the mill about five parts by weight of water and again agitate to form a fairly homogeneous mixture. Usually about 3 minutes more is sufficient. This gives a product of sufficient fluidity to flow well so that the whole contents of the mill including the pebbles may be readily emptied into a vessel in which it may stand.

Very quickly, in fact almost immediately, a stratification takes place. A layer consisting of an aqueous solution of free nicotine sufficiently concentrated for the usual commercial purposes, viz., from about 63 to 70% of nicotine, rises to the top of the vessel, showing a sharp plane of demarcation between itself and the under layer. In regular practice, carrying out the process on a commercial scale, I have recovered in this top 75 layer 81% of the original amount of the nicotine in the starting material.

Beneath the top layer of concentrated aqueous solution of free nicotine is an aqueous solution of sodium carbonate, and below this 80 the lime sludge.

The nicotine solution forming the top layer may be drawn off in any suitable way so as not to unnecessarily agitate the stratified solutions. This may be done by siphoning off 90 the solution of free nicotine, or by drawing it off through a cock located at an appropriate level in the side of the vessel, or through several such cocks at different levels, as will be well understood by chemists.

95 It will be found that the concentrated nicotine solution is particularly free from soda ash or sodium bicarbonate, as the latter seems to be practically insoluble in the strong solution of free nicotine. On the other hand the 100

free nicotine is slightly soluble in the soda-ash solution, and this is the reason, at least in part, why the entire amount of free nicotine is not recovered in the top layer. Also, 5 some of the nicotine will be found in the lime sludge at the bottom of the settling vessel.

Therefore, to reduce the loss, I have found that the solution of sodium bicarbonate or soda ash may be used instead of, or at least 10 to replace some of the water for a succeeding batch of material, thus reducing the loss of nicotine. Preferably the solution of soda-ash is combined with water in the proportion of 9 parts of solution to 1 part of water. 15 Furthermore, by washing the lime sludge with water, the free nicotine of the sludge will be carried into solution in the water and this solution may be used instead of pure water for the succeeding batch. Still better, 20 both steps may be combined, that is, both the solution of nicotine from the sludge washing step and the solution of sodium bicarbonate may be used instead of pure water for the subsequent batch. By this means I have succeeded in reducing materially the loss of free 25 nicotine and have been able to make recoveries as high as 86% of the nicotine in the starting material.

While I have described the process particularly with reference to the use of hydrated lime, it is to be understood that barium hydroxide may be used in place of the hydrated lime. Furthermore, instead of soda ash I may use caustic soda, potassium carbonate or potassium nitrate.

A very important warning is necessary, however, as to the addition of the soda ash or its equivalent, and that is, that it should be used in the solid state and not dissolved in water and then added, for this seems to interfere with the success of the process.

It will be seen from the above description, that the process is a rapid one and is simple enough to be carried out on a large scale 45 with ordinary care and without the services of skilled chemists.

The free nicotine solution as obtained from the process described is ready to go on the market. If, however, it is desired to concentrate or purify it further, this can be done 50 by the usual methods heretofore employed for refining nicotine.

It will be apparent to those skilled in the art, that in my process, the calcium or barium 55 of the hydroxides used by me are metals capable of forming a water-insoluble compound or salt with the acid of the nicotine salt, so that such salt precipitates from the solution. Hence, in carrying out the process 60 in the best way, at least enough of such a hydroxide should be used as to insure the presence of a combining weight of such hydroxide.

On the other hand, the compound of the alkali metal is water-soluble and therefore tends 65

to take the water from the nicotine solution, does not react with the nicotine and is not soluble in the strong nicotine solution, while furthermore the free nicotine is but slightly soluble in the solution of the compound of alkali metal. Furthermore, the amount of such compound of the alkali metal is such as to form a solution with a considerable amount of the water in the original solution of nicotine salt as well as with the water subsequently added, thereby insuring a concentrated solution of free nicotine. 70 75

What is claimed is:

1. The process of recovering nicotine from solutions of its compounds containing an acid radical, which consists in mixing with the solution a hydroxide of a metal which will free the nicotine from its compound and unite with the acid radical to form a water-insoluble body, then combining with the mixture a water-soluble compound of an alkali metal, then adding a liquid comprising water in sufficient quantity to provide a layer of said liquid whose level is above the level of the layer of solids accumulated in the process, 80 then allowing the mixture to stand until a layer of nicotine solution accumulates at the top, and then removing this solution. 85 90

2. The process of recovering nicotine from a solution of its salts, which consists in thoroughly incorporating, with said solution, a hydroxide of a metal capable of forming a water-insoluble compound with the acid of the nicotine salt, the amount of the hydroxide being sufficient to combine with all of the 95 acid present in the nicotine salt, then incorporating a water-soluble compound in solid form which will form an aqueous solution whose density is greater than that of the nicotine solution and in which the nicotine is practically insoluble, said compound being one which will not react with the nicotine, the amount of said compound added being not more than sufficient to form a saturated solution with all the water finally 100 present in the mixture, then adding a liquid comprising water, in sufficient quantity, to form with the preceding mixture a fluid mass which can be poured from one vessel to another, then allowing this fluid mass to stand until stratification takes place with the nicotine solution at the top, and then removing the nicotine solution. 105 110 115

3. The process of recovering nicotine from solutions of its salts, which consists in mixing with the solution a hydroxide of a metal which forms a water-insoluble salt with the acid of the nicotine salt, then combining with the mixture an undissolved water-soluble compound of an alkali metal, then adding water in sufficient quantity to provide a layer of water whose level is above the layer of solids accumulated in the process, then allowing the mixture to stand until it stratifies 120 125 130

with a layer of nicotine solution at the top, and then drawing off the solution.

4. The process of recovering nicotine from its compounds with acids which form water-insoluble calcium salts, which comprises mixing with an aqueous solution of such a nicotine salt of about 40% strength by weight sufficient calcium hydroxide to combine with the acid of the nicotine salt, then incorporating soda ash, then adding more water so that the total amount of water is sufficient to form a layer whose level is above the layer of solids accumulated in the process, allowing the mixture to stand until the concentrated nicotine solution separates, and then withdrawing the separated nicotine solution.

5. The process of recovering nicotine from its salts containing an acid radical which forms an insoluble salt with calcium, which consists in adding about 2½ parts by weight of hydrated lime to 10 parts by weight of an aqueous solution of the nicotine salt of about 40% strength by weight, agitating the mixture, then adding 1 to 1½ parts by weight of soda ash, agitating the mixture further, then adding about 5 parts by weight of water, again agitating, then allowing the mixture to stand until the nicotine solution rises to the top, and then withdrawing the nicotine solution.

6. The process of recovering nicotine from its salts containing an acid radical which forms an insoluble salt with calcium, which consists in thoroughly incorporating about 2½ parts by weight of hydrated lime with 10 parts by weight of an aqueous solution of a nicotine salt of about 40% strength by weight, then incorporating about 1 to 1½ parts by weight of soda ash, then mixing about 5 parts by weight of water, allowing the mixture to stand until stratification occurs, drawing off the nicotine solution at the top, separately drawing off the soda-ash solution, and using the latter solution in place of water for the treatment of a succeeding batch in accordance with the above recited steps.

7. The process of recovering nicotine from its salts containing an acid radical which forms an insoluble salt with calcium, which consists in thoroughly incorporating about 2½ parts by weight of hydrated lime with 10 parts by weight of an aqueous solution of a nicotine salt of about 40% strength by weight, then incorporating about 1 to 1½ parts by weight of soda-ash, then adding about 9 parts by weight of a soda-ash solution obtained from a preceding use of the process and containing some free nicotine, together with 1 part of water, then allowing the mixture to stand until it stratifies with the concentrated solution of nicotine at the top and a layer of solution containing soda-ash beneath it, withdrawing the nicotine solution, separately withdrawing the solution

containing soda-ash, and employing the latter in carrying out the above set forth process with another batch of nicotine salts.

8. In the process of recovering nicotine from its salts, set forth in claim 5, the steps of removing the lime sludge from the bottom of the settling vessel, washing the sludge with water to dissolve any free nicotine contained in said sludge and using this nicotine solution instead of pure water in carrying out the process of claim 5 on a subsequent batch of nicotine solution.

9. In the process of recovering nicotine from its salts, set forth in claim 5, the steps of removing the soda-ash solution, then removing the lime sludge from the bottom of the settling vessel, washing the sludge with water to dissolve any free nicotine contained in said sludge, uniting this wash water nicotine solution with the solution of soda-ash, and using the mixture instead of pure water to carry out the process of claim 5 on a subsequent batch of nicotine salts.

In testimony whereof, I have hereunto set my hand.

HENRY K. McCONNELL.
